METHOD AND APPARATUS FOR CONTROLLING REFRIGERATING MACHINES

Leslie B. M. Buchanan, Springfield, Mass., assignor to Westinghouse Electric & Manufacturing Company, East Pittsburgh, Pa., a corporation of Pennsylvania

Application August 18, 1937, Serial No. 159,657

14 Claims. (Cl. 62—4)

My invention relates to refrigerating machines and it has for an object to provide an improved method and apparatus for controlling the same.

A further object of the invention is to provide 5 an improved method and apparatus for controlling the operation of a refrigerating machine in response to temperature conditions in different zones being cooled.

A further object of the invention is to provide 10 an improved control for a two-temperature refrigerator that will be inexpensive to construct.

A still further object of the invention is to provide 15 an improved control for a refrigerating machine that is responsive to the temperatures of its cooling element and the media cooled by the same.

These and other objects are effected by my 20 invention as will be apparent from the following description and claims, taken in connection with the accompanying drawings, forming a part of this application, in which:

Fig. 1 is a diagrammatic view of a two temperature refrigerator controlled in accordance with my invention;

25 Fig. 2 shows a second form of two temperature refrigerator having my improved control applied thereto; and

Fig. 3 is a diagrammatic view of a refrigerating 30 system employing a single evaporator and controlled in accordance with my invention.

Description—Fig. 1

Reference will now be had to Fig. 1 of the drawings wherein the numeral 10 generally indicates 35 a cabinet structure that defines relatively high and low temperature zones or chambers 11 and 12 for the storage of perishables. High and low temperature evaporators 13 and 14 of suitable construction are disposed within the zones 40 for refrigerating the same and are supplied with condensed refrigerant by a condensing unit, generally shown at 15, and including a compressor 16, driven by an electric motor 17, and a condenser 18. The latter is cooled in any well known 45 manner, such as, for example, by a fan 19.

The refrigerating system which I have chosen 50 to show has the evaporators 13 and 14 connected in series for the flow of refrigerant, the higher temperature evaporator 13 receiving condensed 55 refrigerant from the condenser 18 through a conduit 21 and the refrigerant vaporized in both evaporators being returned to the compressor 16 through a suction conduit 22. A suitable expansion device, such as a high side float valve 23 may be connected in the conduit 21 for reduc-

ing the pressure of the condensed refrigerant to the value maintained in the evaporator 13 by the compressor 16. In order that the evaporators are operated at different pressures and temperatures, a restricting device, such as, for example, a capillary tube 24 is interposed between the evaporators 13 and 14.

During operation of the compressor 16, vaporized refrigerant at relatively low pressure is withdrawn by the compressor 16 from the evaporator 14 and is compressed to a relatively high pressure. The high pressure vapor is conveyed by a conduit 25 to the condenser 18 wherein it is cooled and condensed. Liquid refrigerant is conveyed through the conduit 21 to the evaporator 13, the valve 23 reducing the pressure of the liquid to the pressure of vaporization in the condenser 13. A portion of the liquid is vaporized in the evaporator 13 and the remaining liquid and the gaseous refrigerant pass through the restricting device 24 to the low temperature evaporator 14. Vaporization of the liquid refrigerant is completed in the low temperature evaporator 14 at low pressure and temperature. The difference in temperatures of the two evaporators is obtained by 25 the restricting device 24 which effects a suitable difference in vaporizing pressures.

Heretofore, it has been the practice to control the circulation of refrigerant in a two temperature refrigerator in accordance with temperature 30 conditions in one or the other of the refrigerated zones or to provide separate thermostats which respond to the temperatures in their respective zones for this purpose. When the control is responsive to the temperature of a single zone for effecting its control, the temperature of the other zone will vary substantially, depending upon the heat load thereon. When controlling the circulation of refrigerant from both zones by separate 35 thermostats, the control mechanism is necessarily 40 expensive.

In accordance with my invention, I propose to use a single thermostat, shown generally at 25, and including an expandible bellows 26. The latter is connected to and communicates with a tube 27 having portions shown by way of example as a pair of bulbs 28 and 29. The bulbs 28 and 29 are disposed in heat transfer relation with the respective evaporators 13 and 14 and define containers for a volatile fluid. The thermostat 25 includes a lever member 31 that is actuated by the bellows 26 and which is connected to an electric switch 32, preferably by means of a snap-acting mechanism 33. The switch 32 is connected 50 55 60 65 70 75 80 85 90 95 100

in an electrical circuit 34 for controlling energization of the motor 17.

The charge of volatile fluid in the thermostatic element defined by the bellows 26, tube 27 and 5 the bulbs 28 and 29 is such that liquid is present in only one of the bulbs, and the remaining bulb, the tube 27 and bellows 26 contain gas, the pressure of which is a function of the temperature of the liquid in the bulb. Accordingly, the thermometer 10 stat 25 responds to the temperature of the bulb containing the liquid which is the lower temperature bulb. The lower temperature bulb contains the liquid because its temperature determines the pressure of vaporization of the fluid and any 15 tendency to increase this pressure due to vaporization of liquid which may be present in the other higher temperature bulb is precluded by the condensation of such vaporized fluid in the lower temperature bulb. It will be apparent from the 20 foregoing description that as the temperature of one bulb is reduced below the temperature of the other, the fluid in the other vaporizes and condenses in the bulb whose temperature has been depressed. Therefore, the liquid always collects in the lower temperature bulb and its pressure of vaporization is determined by the temperature of this bulb.

As the bulb 29 is subjected to the lower temperature evaporator 14, it normally determines 30 the pressure in the bellows 26 and, therefore, controls the operation of the thermostat 25. In accordance with my invention, the thermostat 25 is under control of the bulb 29 during inactive periods of the compressor 16 and therefore determines the temperature at which operation of the compressor 16 is initiated. During operation of the compressor 16, I transfer control to the bulb 28 which determines the temperature at which the compressor 16 is stopped. This transfer of 40 control is accomplished by heating the bulb 29 to a temperature in excess of the temperature of the bulb 28. Heating of the bulb 29 may be effected in any suitable manner but, as shown, I employ the relatively warm high pressure refrigerant passing from the condenser 18 to the expansion device 23 for this purpose. Accordingly, 45 a portion of the conduit 21 is disposed in heat transfer relation with the bulb 29 and a portion of the evaporator 14 as shown at 35.

50 Operation—Fig. 1

As shown in the drawings (Fig. 1) the thermostat switch 32 is open and the compressor motor 17 is inactive, the temperature of the bulb 29 being below the value at which the switch 32 is 55 closed. The flow of condensed refrigerant in the conduit 21 is substantially stopped so that the bulb 29 is cooled by the low temperature evaporator 14 to a temperature below that of the bulb 28 and, therefore, the bulb 29 controls operation 60 of the thermostat 25.

When the temperature of the evaporator 14 and its bulb 29 rises to a predetermined value, for example, 25° F., the switch 32 is closed for 65 energizing the motor 17 and initiating operation of the compressor 16. The temperature of the high temperature evaporator 13 at this time is relatively high, for example, 35° F. Circulation of refrigerant through the evaporators is initiated and, as described heretofore, vaporization 70 is effected in the respective evaporators at different temperatures and pressures. The flow of condensed refrigerant in the conduit 21 effects a rise in the temperature of the bulb 29 to a value 75 higher than the temperature of the bulb 28. Ac-

cordingly, control of the thermostat 25 is transferred to the bulb 28 and operation of the compressor is continued until the temperature of the high temperature evaporator 13 and the bulb 28 is depressed to the desired value, for example, 5 23° F., at which time operation of the compressor 15 is terminated by the opening of the switch 32. At this time, the temperature of the low temperature evaporator is depressed to a relatively 10 low value, for example, 10° F.

Control passes from the bulb 28 to the bulb 29 when the compressor 16 is stopped and flow of heat from the condensed refrigerant to the bulb 29 is terminated, it being understood that the temperature of the bulb 29 falls below the temperature of the bulb 28. A complete cycle of operation has now been described.

From the foregoing it will be apparent that I have provided an improved control wherein the circulation of refrigerant is controlled from relatively high and low temperature zones by a single thermostat mechanism and which may be applied to various forms of refrigerating apparatus wherein the minimum temperature of the higher temperature zone is below the maximum temperature 25 of the low temperature zone.

Description and operation of Fig. 2

The system disclosed in Fig. 2 defines a second 30 form of two temperature refrigerator controlled in accordance with my invention. Parts which are common to both systems shown in Figs. 1 and 2 are designated by similar reference numerals. In the present embodiment, the high and low temperature evaporators 13 and 14, respectively, 35 are connected in free communication with each other, the pressure in both being substantially the same. A conventional pressure responsive expansion valve 41 controls admission of condensed refrigerant to the evaporators in response to the 40 pressure therein.

The evaporators are connected in series for the flow of refrigerant with the liquid refrigerant being admitted to the low temperature evaporator 14 and the vapor being withdrawn from the high 45 temperature evaporator 13. In a system of this kind, the valve 41 operates to maintain a constant pressure in the evaporators so that, as the temperature of the evaporator 14 is reduced the amount of liquid refrigerant therein increases 50 and the superheat in the vapor passing to the evaporator 13 is reduced. When the temperature of the evaporator 14 has been depressed to a predetermined value as determined by the setting of the valve 41, liquid refrigerant is carried into the 55 evaporator 13 and is vaporized therein. Heat is therefore abstracted from the media in the chamber 11. In this form of refrigerating system, a conventional liquid reservoir 42 is disposed in the 60 liquid supply conduit 21 for storing variable quantities of condensed refrigerant.

The temperature of the higher temperature evaporator 13 at which the thermostat 25 terminates operation of the compressor 16 should be 65 somewhat higher than the temperature setting of the valve 41 so that passage of liquid to the suction conduit 22 is prevented. This adjustment of temperatures also assures that the bulb 29 will 70 become colder than the bulb 28 after the compressor is shut down. As the operation of the control apparatus shown in Fig. 2 is similar to the apparatus shown in Fig. 1, detailed description thereof is deemed unnecessary.

Description of Fig. 3

In this figure, I have shown my invention applied to a refrigerator structure 43 embodying a space 44 to be cooled and an evaporator 45 disposed for abstracting heat from the space 44. In this type of refrigerating system, the temperature of the space 44 at the time of terminating operation of the compressor is below the temperature of the evaporator 45 at the time of initiating operation of the same. Such application may be found in commercial type refrigerators where it is desired to maintain the temperature of the air above 32° F. and to defrost the evaporator during each cycle.

A condensing unit 15 similar to the unit shown in Figs. 1 and 2 may be employed and its various elements are shown having similar reference numerals for parts thereof which are common to the various embodiments. Refrigerant that is condensed in the condenser 18 is conveyed to the evaporator 45 through the conduit 21, the latter having a suitable expansion valve 46 connected therein. A portion of the conduit 21 is connected in heat transfer relation with the evaporator 45 and the bulb 28 of the thermostat 25. The other bulb 29 of the thermostat is disposed in heat transfer relation with the air in the space 44. The bulb 29 is, therefore, in a relatively cool zone and the bulb 28 in a warmer zone in the space 44. The operation of the system shown in Fig. 3 will now be described.

Operation of Fig. 3

As shown, the switch 32 is open and the compressor 16 and its driving motor 17 are inactive as the temperature of the bulb 29 is below its switch closing value. As the bulb 29 of the thermostat 25 is disposed in a relatively cold zone, its temperature is below that of the bulb 28 and is, therefore, the controlling element of the thermostat 25. As the temperature of the evaporator 45 and the bulb 29 rises to a predetermined value, say 36° F., the switch 32 of the thermostat 25 closes and energizes the motor 17. Operation of the compressor 16 is initiated and vaporization effected in the evaporator 45. The flow of relatively warm liquid in the conduit 21 imparts sufficient heat to the bulb 29 to elevate its temperature above that of the bulb 28. Accordingly, the latter becomes the controlling element of the thermostat 25.

Operation of the compressor 16 continues until the temperature of the air adjacent the bulb 28 is depressed to a predetermined value of say 33° F., at which time the thermostat 25 deenergizes the motor 17. Operation of the compressor 16 is terminated and vaporization of refrigerant in the evaporator 45 is substantially stopped. As the flow of heat to the bulb 29 from the liquid refrigerant is substantially reduced, the temperature of the bulb 29 is depressed to a value below the temperature of the bulb 28 and, therefore, again becomes the controlling element of the thermostat. At this time, the temperature of the evaporator is relatively low or at a value of say 20° F.

From the foregoing, it will be apparent that the air is maintained at a temperature above freezing at all times and that the evaporator operates part of the time at a temperature that will assure defrosting during part of the cycle.

In the various embodiments described heretofore, I have shown a refrigerating machine of the compression type, but it is to be understood that my invention is applicable to other forms of re-

frigerating machines. The specific form of thermostat structure which I have shown is disclosed by way of example and it will be understood that other forms of gas type thermostats may be employed. Furthermore, I have shown bulbs 28 and 29 for containing the volatile liquid in the thermostat but other suitable containers may be employed.

While I have shown my invention in several forms, it will be obvious to those skilled in the art that it is not so limited, but is susceptible of various other changes and modifications without departing from the spirit thereof, and I desire, therefore, that only such limitations shall be placed thereupon as are imposed by the prior art or as are specifically set forth in the appended claims.

What I claim is:

1. In refrigerating apparatus, the combination of a refrigerating machine including an evaporator, a thermostat for starting and stopping operation of the refrigerating machine and having a first thermal responsive element disposed in heat transfer relation with the evaporator and a second thermal responsive element remote- 20 ly disposed with respect to the first-mentioned element and in a region of higher temperature, said elements containing a volatile fluid and being in communication one with the other, and means effective during active periods of the re- 25 frigerating machine for heating said first element to a temperature in excess of the temperature of said second element.

2. In refrigerating apparatus, the combination of means defining relatively low and high tem- 35 perature zones to be refrigerated, a refrigerating machine for abstracting heat from both zones, a thermostat for initiating and terminating operation of said machine and including first and second thermal responsive elements disposed in 40 heat transfer relation with said low and high temperature zones, respectively, said elements being in communication with each other and containing a volatile fluid, and means for heating said element in the low temperature zone to 45 a temperature higher than the temperature of the element in the high temperature zone during active periods of the refrigerating machine, whereby the element in the low temperature zone controls the refrigerating machine when it is 50 inactive and the element in the higher temperature zone controls the machine when it is active.

3. In refrigerating apparatus, the combination of means defining relatively low and high tem- 55 perature zones to be refrigerated, evaporator means for abstracting heat from both zones, means for circulating refrigerant through the evaporator means, a thermostat for controlling the operation of the circulating means and including first and second thermal responsive ele- 60 ments disposed in heat transfer relation with said low and high temperature zones, said elements being communicating and containing a volatile fluid, and means for heating the thermal element associated with the low temperature zone during 65 periods when the circulating means is active and to a temperature in excess of the temperature of the thermal element associated with the high temperature zone, whereby the circulating means is started in response to the temperature of the 70 low temperature zone and is stopped in response to the temperature of the higher temperature zone.

4. In refrigerating apparatus, the combination of means defining relatively low and higher tem- 75

perature zones to be refrigerated, evaporator means for abstracting heat from both zones, a compressor for withdrawing vaporized refrigerant from the evaporator means and for compressing it to a relatively high pressure, a condenser for liquefying the compressed refrigerant, a thermostat for controlling the operation of said compressor and including thermal responsive elements disposed in heat transfer relation with the 5 low and high temperature zones, respectively, said elements being communicating and containing a volatile fluid and means for conveying the liquid refrigerant from the condenser to the evaporator means in heat transfer relation with the element associated with the low temperature zone.

5. The method of controlling the operation of a machine for refrigerating different zones of a refrigerator at different temperatures which 10 includes initiating the refrigeration of the zones in response to a predetermined high temperature of the lower temperature zone, transferring control of the machine to the higher temperature zone during operation of the machine, terminating operation of the machine in response 15 to a predetermined low temperature of the higher temperature zone and returning control of the machine to the lower temperature zone during inactive periods of the machine.

6. In refrigerating apparatus, the combination of relatively high and low temperature evaporators, means for circulating refrigerant through the evaporators, a thermostat for controlling the operation of said circulating means and having 20 first and second thermal responsive elements disposed in heat transfer relation with the high and low temperature evaporators, respectively, and means for heating the thermal responsive element associated with the low temperature 25 evaporator during periods when the circulating means is rendered active by the thermostat.

7. In refrigerating apparatus, the combination of an evaporator structure having relatively high and low temperature portions, a compressor for 30 circulating refrigerant through the evaporator structure, a thermostat for controlling the operation of the compressor and having thermal responsive elements disposed in heat transfer relation with the evaporator portions, respectively, said elements containing a volatile fluid, and 35 means for heating the thermal responsive element associated with the low temperature evaporator portion to a temperature in excess of the temperature of the other of said thermal responsive elements during periods when the compressor is operated for the circulation of refrigerant.

8. In refrigerating apparatus, the combination of relatively low and high temperature evaporators, a compressor for withdrawing gaseous refrigerant from the evaporators and for compressing it to a relatively high pressure, a condenser for condensing the compressed refrigerant, a thermostat for controlling the operation of the compressor and including thermal responsive elements enclosing a volatile fluid and disposed in heat transfer relation with the respective evaporators and means for conveying the liquid refrigerant from the condenser to the evaporators 50 in heat transfer relation with the thermal responsive element associated with the low temperature evaporator.

9. In refrigerating apparatus, the combination of means defining relatively low and high temperature zones to be refrigerated, a refrigerating

machine for abstracting heat from both zones, a thermostat for initiating and terminating operation of said machine and including first and second thermal responsive elements disposed in heat transfer relation with said low and high 5 temperature zones, respectively, and means for rendering said first and second thermal responsive elements active and inactive, respectively, during periods when the refrigerating machine is stopped and for rendering the first and second 10 thermal responsive elements inactive and active respectively, during operating periods of the refrigerating machine.

10. In refrigerating apparatus, the combination of means defining a zone to be cooled, an evaporator for cooling the media in said zone, means for condensing refrigerant vaporized in the evaporator, a thermostat for controlling the operation of the condensing means and including first and second thermal responsive elements, one of said 20 thermal responsive elements being disposed in heat transfer relation with the evaporator and the other thermal responsive element being disposed in heat transfer relation with the media cooled by the evaporator, said elements being in 25 communication with each other and containing a volatile fluid, and means for heating the element associated with the evaporator during periods when said condensing means is active.

11. In refrigerating apparatus, the combination of means defining a zone to be cooled, an evaporator for cooling media in said zone, means for condensing refrigerant vaporized in the evaporator, a thermostat for controlling the condensing means and including first and second thermal 30 responsive elements, one of said thermal responsive elements being disposed in heat transfer relation with the evaporator and the other thermal responsive element being disposed in heat transfer relation with the media cooled by the evaporator, said elements being in communication with each other and containing a volatile fluid, and means for conveying the refrigerant condensed by the condensing means to the evaporator in heat 35 transfer relation with the thermal element associated with the evaporator.

12. In refrigerating apparatus, the combination of a cabinet embodying a space to be cooled, an evaporator disposed for cooling the media in the space, a compressor for withdrawing vaporous refrigerant from the evaporator and for compressing the same, means for condensing the compressed refrigerant, a motor for driving the compressor, a gas type thermostat for controlling energization of said motor and including first and second thermal responsive elements, one of said 50 thermal responsive elements being disposed in heat transfer relation with the evaporator and the other thermal responsive element being disposed in heat transfer relation with the media cooled by the evaporator, said elements being in communication with each other and containing a volatile fluid, and means for conveying the condensed refrigerant from the condenser to the evaporator in heat transfer relation with the element associated with the evaporator.

13. In refrigerating apparatus, the combination of a cabinet defining a space to be cooled, an evaporator disposed for cooling the media in the space, a compressor for withdrawing vaporous 55 refrigerant from the evaporator and for compressing the same, means for condensing the compressed refrigerant, a motor for driving the compressor, a switch for controlling the energization of the motor, an expansible bellows for actuating 60

75

the switch and including first and second containers for a volatile fluid, one of said containers being disposed in heat transfer relation with the evaporator and the other container being disposed in heat transfer relation with the media cooled by the evaporator, said bellows and containers being in communication one with the other and means for conveying the condensed refrigerant from the condenser to the evaporator in heat transfer relation with the container associated with the evaporator.

14. In refrigerating apparatus, the combination of means defining a zone to be cooled, an evaporator for cooling the media in said zone, means for condensing refrigerant vaporized in the evaporator, a thermostat for controlling the

operation of the condensing means and including first and second thermal responsive elements, one of said thermal responsive elements being disposed in heat transfer relation with the evaporator and the other thermal responsive element being disposed in heat transfer relation with the media cooled by the evaporator, and means for rendering said first and second thermal responsive elements active and inactive, respectively, during periods when the refrigerating machine is stopped and for rendering the first and second thermal responsive elements inactive and active, respectively, during operating periods of the refrigerating machine.

15

LESLIE B. M. BUCHANAN.
